UNITED STATES PATENT OFFICE.

HENRY H. ALTHOFF, OF NEW YORK, N. Y.

DESIGN FOR A GRAVE-INCLOSURE.

44,884.

Specification for Design.

Patented Nov. 18, 1913.

Application filed September 30, 1913. Serial No. 792,694. Term of patent 14 years.

To all whom it may concern:

Be it known that I, HENRY H. ALTHOFF, a citizen of the United States, and a resident of the city of New York, Middle Village, borough of Queens, in the county of Queens and State of New York, have invented a new, original, and ornamental Design for a Grave-Inclosure, of which the following is a specification, reference being had to the accompanying drawing, forming part thereof.

I claim:

The ornamental design for a grave inclosure, as shown.

HENRY H. ALTHOFF.
